UNITED STATES PATENT OFFICE.

WILLIAM H. THEOBALD, OF NEW YORK, N. Y.

ENVELOPE.

SPECIFICATION forming part of Letters Patent No. 466,382, dated January 5, 1892.

Application filed February 24, 1891. Serial No. 383,028. (No model.)

To all whom it may concern:

Be it known that I, WILLIAM H. THEOBALD, a citizen of the United States, residing at New York city, in the county of New York 5 and State of New York, have invented certain new and useful Improvements in Envelopes, of which the following is a specification, reference being had therein to the accompanying drawings.

10 My invention relates to the improvement of envelopes, and it especially relates to envelopes designed to inclose registered letters or packages sent between United States post-offices.

15 The object of my invention is to provide an envelope of novel construction which may be simple and economically made, and also to be so constructed that it cannot be opened without the mutilation of some of its parts.

20 I attain these objects by the construction illustrated in the accompanying drawings, in which—

Figure 1 is a bottom view of the envelope constructed in accordance with my invention, 25 being shown open to receive letters or packages, the arrangement of one of the flaps being also shown in dotted lines, as when closed. Fig. 2 is a face view of the envelope closed and fastened, the protecting-flaps being indicated in dotted lines. Fig. 3 is a rear view of the envelope closed. Fig. 4 is a view of the inner side of the envelope-blank having the lines on which it is to be folded shown by dotted lines. Fig. 5 is a view of the envelope-blank having the long flap slightly 30 modified in form. Fig. 6 is a bottom view of the open envelope produced by said blank.

In said drawings, A represents the body of the blank, which is folded to provide the rear 40 face a and the front face b with the four flaps of the envelope, said flaps being given the form and arrangement relatively to each other as follows: A substantially rectangular flap d, suitably gummed and projecting from one side of the face b, is to secure the long 45 edge of the face a after the latter has been folded upon the face b. A substantially rectangular flap c, (having the corners cut off,) projecting from one end of the face b, is to 50 be folded upon one end of the face a to secure one end of said faces together, and thus close one end of the envelope. A long flap

f, equal in length to or longer than the envelope, projects from the opposite end of the face b, and is the movable closing-flap of the 55 envelope, and a substantially rectangular flap e, of nearly half the length of the envelope and projecting from the unattached end of the face a, is adapted to be folded or tucked in over and partly around the letters or package placed within the envelope. The sealing-flap f has a portion of its length of the same width as the envelope and the balance preferably tapered, so that its outer end is about one-fourth the width of the envelope, its length 60 being equal to the length of the envelope; but it is, in addition, preferably provided with a tongue f², to be folded over and around the end of the envelope and adapted to be secured (in addition to its gummed surface) by 65 a staple, eyelet, or rivet g or other permanent metal fastening, which is made to pass through the doubled portion of said flap, as well as through the faces a and b and the flap c. Said rivet may also be made to pass through one 70 end of the inclosed package. The sealing-flap f is also provided with gummed edges adapted when the envelope is closed to be pressed down upon the face a and the flaps c d. Said rivet may also be made to pass through one 75 end of the inclosed package. The sealing-flap f is also provided with gummed edges adapted when the envelope is closed to be pressed down upon the face a and the flaps c d.

In the modification shown in Figs. 5 and 6 80 85 the long flap f has only one of its edges beveled, so that said edge forms a more acute angle with its straight portion, and while bringing its end near the corner of the envelope when folded and secured allows more room for printed directions on the face a of the envelope under said beveled edge of the long flap.

In use the letter or package to be secured in the envelope is placed in at the open end, 90 after which the small flap e is tucked in loosely around said letter or package. The extended sealing-flap f is then turned over and secured in the manner hereinbefore described, thus fully protecting all the parts and providing 95 a double fastening for all connected parts. To open the package, it is only necessary to cut the large sealing-flap f from Y to Y, as indicated in Fig. 4, on the line where it folds over the open end of said envelope.

100 The envelope described is adapted only for registered letters or packages in the United States mail service. The construction described produces a very strong and safe en-

velope. It is conveniently closed, and when secured it cannot be opened or tampered with without mutilating the parts.

It is obvious that printed directions or such other printed matter as required may be placed on the front and rear face of the envelope to adapt it to the use for which it is especially desired, the printing on the rear face being so located that the writing made by the postmaster will preferably be partly on the face *a* and partly on the flap *f*.

Having now fully described my invention, I claim—

1. An envelope having, besides the side and end flaps to unite the bottom face to the top face thereof, a flap on one end of the bottom face adapted to be folded and tucked in the

envelope and on one end of the top face a flap adapted to extend to the opposite end of the envelope, substantially as described. 20

2. An envelope having, besides the side and end flaps to unite the bottom face to the top face of the envelope, a flap on one end of the bottom face and on one end of the top face a flap adapted to extend to the opposite end 25 and around said end of the envelope, substantially as described.

In testimony whereof I affix my signature in presence of two witnesses.

WILLIAM H. THEOBALD.
